(57) **CLAIM**

The ornamental design for a mosquito lamp, as shown and described.

DESCRIPTION

FIG. 1 is a perspective view of a mosquito lamp design showing my new design.

FIG. 2 is a front view of a mosquito lamp.

FIG. 3 is a rear view of a mosquito lamp.

FIG. 4 is a left side view of a mosquito lamp.

FIG. 5 is a right side view of a mosquito lamp.

FIG. 6 is a top view of a mosquito lamp; and,

FIG. 7 is a bottom view of a mosquito lamp.

The broken lines in the drawings depict portions of the mosquito lamp that form no part of the claimed design.

1 Claim, 7 Drawing Sheets(56)
